John H. Board

UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

METHOD OF MAKING SHOES.

1,215,304.

Specification of Letters Patent.

Patented Feb. 6, 1917.

Application filed April 22, 1915. Serial No. 23,100.

To all whom it may concern:

Be it known that I, ARTHUR BATES, a subject of the King of England, residing at Leicester, Leicestershire, England, have invented certain Improvements in the Methods of Making Shoes, of which the following description, in connection with the accompanying drawings, is a specification, like reference characters on the drawings indicating like parts in the several figures.

This invention relates to processes of making shoes and in particular to improvements in processes of making shoes which involve molding the shoe upper.

15 An important object of the present invention is to produce a shoe which is both light and durable and which can be manufactured with a minimum of labor and expense.

More particularly the invention aims to 20 reduce the number of steps performed in making a shoe of the type herein shown and at the same time to reduce the amount of material required to produce said shoe without affecting the quality of the shoe.

25 Other objects and features of the invention will appear from the following description and claims when considered in connection with the accompanying drawings in which,—

30 Figure 1 is a perspective view of a shoe embodying this invention, the heel end of the shoe being shown partly in section; and

Fig. 2 is a perspective view of a sole used in making the preferred form of the shoe 35 of this invention.

In carrying out the process of this invention in one manner in which it has been successfully practised, the heel end of the shoe upper 3 is first molded, preferably by 40 a machine of the type shown and described in the specification of application for British Letters Patent No. 10,360 of 1914, to provide an inturned flange 5 extending about the heel end of the upper. The heel

45 portion of the sole 6 is then split or gouged out so as to form a flap or tongue 8, the full thickness of the sole being retained around the marginal edge of the sole to provide a rand shoulder 9. The upper with the counter and lining is then assembled upon a last and pulled over in the usual manner, the inturned flange 5 of the upper being positioned between the flap or tongue 8 and the heel end of the sole 6. The forepart of the 50 shoe is then lasted in the usual manner and

the outturned flange 12 of the upper about the forepart of the shoe secured to the sole by stitches 15. At this stage in the process the heel end of the shoe, including the flap 8, the marginal edge of the upper and the heel portion of the sole are loosely assembled on the last in the relative positions they are to occupy in the finished shoe, that is, with the inturned flange 5 of the upper interposed between the flap 8 and the heel end of the sole. In the next step of this process, the several parts of the shoe at the heel, together with a heel 16 if a heeled shoe is to be produced, are secured together in a single operation by fastenings 18 which are positioned so as to pass through the heel, sole, and inturned flange of the upper and are clenched upon the upper surface of the flap.

It will be noted that the shoe produced by this process has only a single set of fastenings in the heel end thus effecting a saving of labor and material over the present practice of lasting the heel portion of the upper on to a heel seat independently of the heel seat nailing and heel attaching operations and also providing a more comfortable and satisfactory heel seat for the shoe.

It will be further noted that the flap or tongue 8 is formed in the heel end of the sole in such a manner that the marginal edge 9 of the sole at the heel provides a shoulder to support the rounded lower edge of the counter and prevent it from running over. The extra thickness about the marginal edge of the heel end of the sole also acts as a rand to compensate for the curvature of the bottom face of the heel of the last, thereby providing a flat heel seat upon which to nail the heel or if a spring heel shoe is to be produced, the formation of the sole at the heel enables the offset heel portion of the sole to present a substantially horizontal wearing surface.

Having described my invention, I claim 100 as new and desire to secure by Letters Patent of the United States:—

1. That improvement in the art of making shoes which consists in molding the heel end of an upper to provide an inturned flange, splitting the heel end of the sole to form a flap, assembling the upper and sole upon a last with the inturned flange of the upper positioned between the flap and the heel end of the sole, and securing the heel por- 110

tion of the sole to the inturned flange of the upper and the flap in a single operation.

2. That improvement in the art of making shoes which consists in molding the heel end 5 of an upper to provide an inturned flange, forming a tongue upon the heel end of the sole in such manner that the original thickness of the sole is retained about the marginal edge thereof, assembling the upper 10 and sole upon a last with the inturned flange extending between the flap and the heel end of the sole, securing the upper to the sole about the forepart, and securing together the heel portion of the sole, the in- 15 turned flange of the upper and the flap in one operation.

3. That improvement in the art of making shoes which consists in splitting the heel end of a sole, molding the heel end of 20 an upper to provide an inturned flange,

assembling the upper and sole upon a last with the inturned flange of the upper positioned between the split portions of the heel end of the sole, securing the upper to the sole about the forepart, and securing together the split portions of the sole and the flange of the upper simultaneously. 25

4. That improvement in the art of making shoes which consists in molding the heel end of an upper to provide an inturned flange, 30 splitting the heel end of the sole to form a flap, assembling the upper and sole upon a last with the inturned flange of the upper positioned between the flap and the heel end of the sole, and securing the heel portion of the sole and a heel to the inturned flange of the upper and the flap in a single operation. 35

In testimony whereof I have signed my name to this specification.

ARTHUR BATES.
